Des. 185,392
Patented June 2, 1959

185,392

ELECTRIC COOKING STOVE

Donald A. Smith, Wheaton, Ill., assignor to General Electric Company, a corporation of New York

Application February 20, 1958, Serial No. 49,725

Term of patent 3½ years

(Cl. D81—4)

Fig. 1.

Fig. 2.

Fig. 1 is a perspective view of an electric cooking stove embodying my new design.

Fig. 2 is a vertical section taken on lines 2—2 of Fig. 1.

The dominant features of the design reside in the portions shown in full lines.

I claim:

The ornamental design for an electric cooking stove, substantially as shown and described.
